Primary Examiner — Rashida C. Walshon(74) Attorney, Agent, or Firm — Morgan Lewis & Bockius LLP(57) CLAIM

The ornamental design for a fashion loop, as shown and described.

DESCRIPTION

FIG. 1 is a bottom, rear, perspective view of a fashion loop showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a left-side cutaway view thereof showing a portion of the left side of the fashion loop visible in an interior of an unclaimed boot;

FIG. 7 is a top plan view thereof; and,

FIG. 8 is a bottom plan view thereof.

The broken lines illustrate structure or features that form no part of the claimed design.

1 Claim, 8 Drawing Sheets(56)
